PAIL HOLDER FOR LADDERS

William P. Kunde, Berwyn, Ill.

Refiled for abandoned application Serial No.
228,105, September 2, 1938. This application
July 17, 1940, Serial No. 345,937

1 Claim. (Cl. 248—211)

This invention relates to a new and improved type of pail holder for ladders, as more fully illustrated by the preferred embodiment herein described.

5 The present application is a substitute for Serial No. 228,105, filed September 2, 1938, and now abandoned.

10 One of the objects of the invention is to provide a new and improved type of pail holder to be used on ladders for holding paint buckets and the like.

15 A further object of the invention is to provide a pail holder of the type described which can be employed on either the right side or the left side of a ladder.

20 Still another object of the invention is to provide a new and improved type of pail holder of the type described which affords uniform distribution of the weight of a bucket or the like supported thereby from a ladder.

25 Another object of the invention is to provide a compact, inexpensive type of pail holder for ladder work made from a single piece of sheet metal.

Still a further object of the invention is to provide 30 a new and improved type of pail holder of the type described which holds the pail close to the upright of the side of the ladder and is provided with means to prevent the pail from being accidentally displaced.

35 Other features and advantages of the invention will appear by reference to the following description thereof in conjunction with the accompanying drawing which illustrates the preferred embodiment of the invention and in which:

40 Figure 1 illustrates a ladder in combination with a pail holder of the present invention shown mounted on the right side of the ladder;

45 Figure 2 illustrates the use of the pail holder of the present invention when mounted on the left side of the ladder;

50 Figure 3 is a side view of the ladder showing the manner in which the pail holder supports the pail;

55 Figure 4 is a front view of the ladder with the pail holder mounted on the right side of the ladder upright, as in Figure 1.

Referring to the drawing and particularly to Figure 4, it will be seen that the pail holder of the present invention consists of a single piece 50 of sheet metal in two integral sections including an L-shaped section A and a substantially inverted U-shaped section B. For convenience in description, the L-shaped section A may be described as having a base portion 2 and a top portion 4. The base portion 2 and the top por-

tion 4 intersect at point 6 substantially at right angles to each other. Both the base portion 2 and the top portion 4 have substantially flat inner surfaces adapted to fit against the upright of the average ladder. Both also have substantial 5 vertical depth x which may be, for example, according to one preferred embodiment of the invention, about $1\frac{1}{8}$ inches. The base portion 2 also has a substantial length y which preferably extends at least halfway through the depth of the 10 ladder upright and is preferably such that the pail holder 8 is near the middle of the side of the ladder upright, as shown by Figure 3.

The top of the L-shaped portion 4, as previously indicated, is a continuation of the base 15 portion 2 and is integral therewith, being also preferably of the same depth x , as shown by the illustration in Figure 4.

The inverted substantially U-shaped portion B, 20 as shown in Figure 4, is integral with the top edge of the L-shaped portion A and comprises an upwardly extending section 10 and a downwardly extending section 12 with an intermediate section 14 adapted to fit over the rung 16 of a ladder, as shown in Figure 3.

25 The edges of said inverted U-shaped section, adapted to be disposed adjacent the ladder upright, fall in a plane B'-B' substantially parallel with the inside of the ladder upright and also substantially parallel with the inside of the base 30 portion 2 of the L-shaped section A, as shown in Figure 4. The upper side of the L-shaped portion 4 is of substantial length and may be, for example, about $2\frac{1}{2}$ inches, in accordance with the preferred embodiment of the invention. The 35 inverted U-shaped member B may be somewhat smaller in width than the vertical depth x of the L-shaped member A. The distance z , as shown in Figure 4, between the plane B'-B' and the plane running through the inside of the base 40 member 2 of L-shaped section A should preferably be slightly greater than the width of the ladder upright.

It is a feature of this invention that the pail 45 holder described may be employed either on the right side of the ladder, as shown in Figure 1, or on the left side of the ladder, as shown in Figure 2. In either case the bail 18 of the bucket 20 is supported by the stamped-out metal hook 8. In order to prevent the accidental dislodgment of the bail, the metal hook 8 is recessed 50 slightly at point 22 so that it is somewhat wider at this point than thereabove. The weight of the bucket 20 pulls downwardly against the stamped-out hook member 8. At the same time 55

the weight is distributed against the side of the upright of the ladder through the base 2 of the L-section A and since this is of substantial depth, the weight of the bucket is distributed over a substantial area of the side of the ladder upright. The tendency of the base portion 2 to press inwardly against the outside of the ladder upright is counteracted to some extent by the arrangement of the inverted U-shaped portion 10 B, which will tend to press against the inside of the ladder upright in an opposite direction, thereby further tending to distribute the weight over another portion of the area of the ladder upright. If the pail holder is used on the right 15 side of the ladder, a part of the weight of the bucket is also distributed over the top of the right ladder upright through section 4 of L-shaped section A, assuming that the ladder is placed on a slant in the usual manner, as shown 20 in Figure 1. The distribution of the weight in this manner tends to take away from the rung of the ladder much of the weight of the bucket, and since the rung of the ladder ordinarily is the first part of the ladder to wear out, it is desirable not to accelerate this wear any more 25 than necessary.

The particular arrangement and construction of the pail holder is such, as previously explained, 30 that the edges of the inverted U-shaped member B fall in a plane substantially parallel and closely adjacent to the inside of the ladder upright, regardless of whether the pail holder is placed on the right or left side of the ladder. 35 The inside of the base section 2 of the L-shaped member A is adapted to fit against the outside of the ladder upright so that any tendency of the pail holder to slip from side to side is counteracted on the one hand by the edges of the 40 inverted U-shaped member B and on the other

hand by the flat base section 2 of the L-shaped member A.

The pail holder requires no special means for fastening it to the ladder upright regardless of whether it is used on the left side or the right 5 side of the ladder. This is an important feature of the invention because heretofore it has been customary to provide a special hook or means to prevent the pail holder from moving from side to side and such means have been adapted only 10 for pail holders that were to be used on the right side of the ladder. The present invention, therefore, provides for the first time a simple, compact, inexpensive type of pail holder made from a single piece of sheet metal which may be used 15 on either side of a ladder to hold the pail against the side of the ladder while providing against accidental dislodgment thereof.

It will be understood that certain variations 20 may be made in the invention described without departing therefrom. The pail holder illustrated is preferably made from a single piece of sheet metal which, for all practical purposes, is substantially rigid, although it may have very slight flexibility. However, the pail holder can 25 be made from other materials of construction having the necessary strength.

Having thus described the invention, what I 30 claim as new and desire to secure by Letters Patent of the United States is:

A bucket support for use with a ladder constructed of an L-shaped metal sheet having one leg bent in the form of a hook for engaging the rung of a ladder and having the other leg bent 35 at right angles intermediate its ends to provide portions for engaging the front and side of an upright of a ladder, the side engaging portion being provided with a struck-out hook for receiving the bail of a bucket.
